UNITED STATES PATENT OFFICE.

IRVEL J. GRIGNON, OF DULUTH, MINNESOTA.

CIGARETTE CASE.

Application filed November 5, 1925. Serial No. 67,005.

The invention relates to cigarette cases, and has for its object to provide a device of this character comprising hingedly connected sections having compartments and in the outer end of one of said compartments a hingedly mounted lighter frame, which is normally forced outwardly by means of a spring provided with a lighter, and which lighter frame upon the opening of the cigarette case is forced outwardly to a position where it may be used. The lighter frame is held within the cigarette case section by the engagement therewith of the hinged cover of the case.

A further object is to provide the case section in which the lighter is disposed with a transversely disposed partition, which divides the case into a cigarette section and a lighter section thereby maintaining the cigarettes out of engagement with the hinged lighter.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a plan view of the cigarette case showing the same open and the lighter in position to fly outwardly under the influence of its spring.

Figure 2 is a top plan view of the case showing the same open and the lighter in position to move outwardly.

Figure 3 is a perspective view of the case.

Referring to the drawing, the numeral 1 designates the main section of the cigarette case, which is preferably oblong shaped as shown and hingedly connected at 2 to the main section 1 is a cover 3. The cover 3 is provided with a lug 4, which engages over the spring catch 5 in the usual manner for maintaining the cover in closed position. Hingedly connected at the hinging point between the main body 1 and cover 3 is a spring actuated arm 5 which is adapted to engage the outer sides of a plurality of cigarettes 6, within the main body 1 and maintaining the same therein for allowing easy removal of the cigarettes as desired.

The main body 1 of the case is divided into a cigarette compartment 7 and a lighter

compartment 8 by means of a transversely disposed partition 9 adjacent its outer end, and which partition also prevents the cigarette from coming into engagement with the lighter 10 and preventing its proper operation or movement outwardly to the dotted line positions shown in Figures 1 and 2 when the cover is open.

The lighter 10 extends transversely of the casing 1 within the lighter chamber 8 and is provided with arms 11, which are pivotally mounted on a rod 12 at the outer side of the chamber 8. Surrounding the rod 12 is a coiled spring 13, one arm 14 of which engages the bottom of the chamber 8 and the other arm 15 engages under one of the lighter arms 11, therefore it will be seen that when the cover 3 is released the coiled spring 13 will force the lighter as a whole outwardly through the dotted line positions shown in Figures 1 and 2 where it can be utilized by the operator for lighting a cigarette. The lighter is maintained within the chamber 8 by the cover 3 when said cover is closed, but as soon as the cover is released, the spring 13 immediately forces the lighter outwardly to the dotted line position shown, and in which position the lighter may be easily manipulated for lighting the cigarette. The outward movement of the lighter is limited by the engagement of the arms 11 with the flange 16 of the main section 1 of the case, and will be held in said position by the spring 13 until it is manually moved inwardly to the chamber 8, against the action of the coiled spring 13.

From the above it will be seen that a cigarette case is provided which is simple in construction, and provided with a hinged cigarette lighter which is immediately forced to position for use upon the release of the cigarette case cover. It will also be seen that a smoker will at all times have facilities for lighting a cigarette and that the cigarettes within the case will not interfere with the operation of the lighter.

The invention having been set forth what is claimed as new and useful is:—

1. A lighter case and mounting therefor comprising hingedly connected sections, fastening means for the free ends of said sections, a hingedly mounted lighter within a chamber of one of said sections adjacent its free end, spring means for normally forcing said lighter outwardly to a position outside and beyond the end of the section to

which it is hingedly connected, upon the release of a fastening means, said sections when in closed position forming means for maintaining the lighter within the chamber of one of the sections against the action of the spring means.

2. A lighter case and mounting therefor comprising a main body section having a chamber therein, a cover section hingedly connected to the body section, a cigarette lighter disposed in a chamber of the main body section, a rod adjacent the outer end of the main body section within the chamber, arms carried by said lighter and hingedly mounted on the rod, a spring surrounding the rod, an end of said spring engaging the bottom of the chamber of the main body section, an end of said spring en-

gaging under one arm, said spring forming means whereby said lighter will be forced outwardly to operative position upon release of the cover, said arms of the lighter cooperating with the end of the body section whereby the outward movement of the lighter is limited.

3. A lighter case and mounting therefor comprising a chambered main section, a cover section hingedly connected thereto, a hinged spring actuated lighter disposed in the outer end of the main section, said lighter being maintained within the section by the cover section when closed.

In testimony whereof I have signed my name to this specification.

IRVEL J. GRIGNON.
